(57) **CLAIM**

The ornamental design for a golf ball retriever for a golf cup, as shown and described.

DESCRIPTION

FIG. 1 is a top front left perspective view of the golf ball retriever for a golf cup of the present invention;

FIG. 2 is a top front right perspective view thereof;

FIG. 3 is a bottom front left perspective view thereof;

FIG. 4 is a bottom front right perspective view thereof;

FIG. 5 is a top view thereof;

FIG. 6 is a bottom view thereof;

FIG. 7 is a left side view thereof;

FIG. 8 is a front view thereof;

FIG. 9 is a right side view thereof;

FIG. 10 is a rear view thereof; and,

FIG. 11 is a top perspective environmental view thereof illustrating the golf ball retriever for a golf cup being inserted into a golf cup.

The portions of the golf ball retriever for a golf cup illustrated in broken lines forms no part of the claim for the golf ball retriever for a golf cup design.
